CLAIM

The ornamental design for a “chair”, as shown and described.

DESCRIPTION

FIG. 1 is a perspective view of the chair;

FIG. 2 is a back view of the chair;

FIG. 3 is a side view of the chair;

FIG. 4 is a front view of the chair;

FIG. 5 is a top view of the chair; and,

FIG. 6 is a perspective view of a second embodiment of the chair wherein the sole difference is the absence of seam lines.

FIGS. 3 and 5 have been shown on a reduced scale with respect to the other views.
